UNITED STATES PATENT OFFICE.

FRANKLIN B. PEASE, OF ROCHESTER, NEW YORK.

DESIGN FOR A VELOCIPED-E-SUPPORT.

SPECIFICATION forming part of Design No. 32,181, dated January 30, 1900.

Application filed December 18, 1899. Serial No. 740,827. Term of patent 14 years.

To all whom it may concern:

Be it known that I, FRANKLIN B. PEASE, of Rochester, in the county of Monroe, in the State of New York, have invented and produced a new and original Design for Velocipede-Supports, of which the following is a specification, reference being had to the accompanying drawings, forming part thereof.

Figure 1 is an isometric view of a velocipede-support embodying my design. Fig. 2 is a top plan of said support.

The leading feature of my design consists in a velocipede-support which when viewed in perspective from one end presents substantially the appearance of a rectangle having opposite sides of its base formed of inverted-T shape and having its central portion formed with upright substantially parallel separated bars provided with downwardly-diverging branches.

A B C C D are respectively top, bottom, side, and intermediate bars of a velocipede-support embodying my design. E E are the base-pieces of said support, and F are the downwardly-diverging branches of the upright bars C C D. The top and bottom bars A B are arranged in substantially horizontal planes and the side and intermediate bars C C D in substantially vertical planes. The base-pieces E E extend from front to rear at

the points of union of the bottom and side bars B C C, with their outer faces in substantially the same planes as the outer side faces of the side bars C C, are formed with ornamented front and rear ends e, and are connected at their extremities by cross-bars e', arranged substantially parallel with the top and bottom bars A B and in substantially the same plane as the bottom bar B. The downwardly-diverging branches F extend from substantially the central portions of the side and intermediate bars C C D to the front and rear ends of the base-pieces E E and to the cross-bars e'.

A velocipede-support embodying my design presents a graceful, pleasing, and characteristic appearance.

What I claim is—

The design for a velocipede-support, substantially as herein shown and described.

In testimony whereof I have hereunto signed my name, in the presence of two attesting witnesses, at Rochester, in the county of Monroe, in the State of New York, this 5th day of December, 1899.

FRANKLIN B. PEASE.

Witnesses:

JOHN H. DAILEY,
JOSEPH L. HUMPHREY.
